FURNACE

Jesse O. Betterton, Metuchen, and Melville F. Perkins, Woodbridge, N. J., assignors to American Smelting and Refining Company, New York, N. Y., a corporation of New Jersey

Application August 14, 1934, Serial No. 739,720

13 Claims. (Cl. 263—43)

This invention relates to furnaces.

The invention provides an improved furnace having a wide application in the chemical and metallurgical arts and is of particular importance in conducting volatilizing operations, especially those which are ordinarily effected only with difficulty.

Furnaces embodying the principles of the invention have proved of signal importance in volatilizing a host of different compounds, materials and substances both pure and impure and in vaporizing and/or subliming many of the oxides, sulfides, chlorides, etc. of arsenic, antimony, cadmium, lead, selenium, tellurium, zinc and the like, as well as various mixtures thereof. In such furnaces, remarkably improved results have been attained. Further, the invention permits such reactions as oxidation, reduction, halogenation and sulphatization to be readily practiced under precisely controlled conditions and any such reaction can be readily inaugurated to be continued indefinitely or, if desired, changed at will.

In accordance with the invention, a furnace is provided having means for simultaneously heating a charge and subjecting same to the action of an atmosphere of appropriate, controlled temperature and desired chemical composition.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a longitudinal section through a furnace constructed in accordance with the invention,

Fig. 2 is a cross-section of the furnace shown in Fig. 1, taken along the line 2—2,

Fig. 3 is a section through a modified form of furnace embodying the invention, and

Fig. 4 is a section through a further modified form of furnace embodying the invention.

In the following description and in the claims, various details will be identified by specific names for convenience, but they are intended to be as generic in their application as the art will permit.

Referring now to Figs. 1 and 2, there is shown a furnace of the muffled-flame type having fire tubes 10 and 11 extending from the burner end of the furnace through a partition 12, which

burners 15 (one shown) are operatively associated with fire tubes 10 and 11, the latter being composed of silicon carbide and set in asbestos cement 16 at the burner end and a suitable highly refractory cement 17 in partition 12. Charge hoppers 18 and 19, equipped respectively with slide valves 20 and 21, open to the laboratory of the furnace 22 via feed ducts 23 and 24 respectively. Gas-tight work door 25 permits access to the laboratory of the furnace and a tap hole 26 equipped with removable plug 27 is provided at the lowest point of hearth 28. Pyrometer 29 extends through the side wall into the furnace laboratory. Positioned above the hearth of the furnace are inlet baffle 30 and outlet baffle 31. Vent 32 of chamber 14 is equipped with damper 33, and inspection door 34, sampling tube 35 equipped with pressure gauge 36, and auxiliary gas inlet 37 are provided in wall 13. Port 38 leads from chamber 14 to the laboratory of the furnace and outlet port 39 leads from the latter to the flue system 40.

In the modified form of furnace shown in Fig. 3 the laboratory of the furnace is of increased dimension, the partition 41 serving both as an additional baffle and as a support for the joint between fire tubes 42 and 43. In other respects the furnace structure is similar to that shown in Figs. 1 and 2 and the analogous parts are indicated by the reference characters bearing the suffix *a*. In the modified form shown in Fig. 4, 44 is a kettle positioned over fire box 45 associated with burner 46 and flue 47. The superstructure of the furnace is carried by steel members 48 and 49 supported by I-beams 50. Charge hopper 51 having screw conveyor 52 communicates with feed duct 53 via slide valve 54. The kettle 44 and fire box 45 are suitably mounted (not shown) for raising and lowering same into and out of operating position. In other respects the apparatus is similar to that shown in Figs. 1 and 2 as indicated by the analogous reference characters bearing the suffix *b*.

In operation the material to be treated is placed in hoppers 18 and 19 and supplied to the hearth of the furnace through feed ducts 23 and 24 by suitable manipulation of slide valves 20 and 21. Obviously the feeding may be continuous or intermittent, the former, however, having been found more advantageous for most operations involving the use of the furnace as a volatilizing unit. Suitable fuel is supplied by burners 15 and burned in the fire tubes 10 and 11 which produce a muffled flame from which the gases comprising the products of combustion pass into chamber 14.

By suitable regulation, the composition of the combustion gases may be accurately controlled over a wide range from reducing through neutral to oxidizing. Further, their composition may be altered if necessary or desirable by the introduction of auxiliary gases through inlet 37, some of these auxiliary gases for particular purposes being oxygen or air, sulphur dioxide and chlorine. In any event, the gases in chamber 14 are supplied to the laboratory of the furnace through port 38 in a uniform stream of definite and desired composition.

As the gases pass into the laboratory of the furnace they strike baffle 30 which causes them to be impinged against the surface of the charge which action is of vital importance as will be later pointed out. In order to leave the furnace, the gases must pass under exit baffle 31 with the result that the moving gas stream sweeps the charge during the entire duration of its passage through the laboratory of the furnace. The sweeping gases then pass out of the furnace through outlet port 39 into flue system 40 which may lead to a bag filter or other suitable recovery apparatus.

In the modification shown in Fig. 3 an additional baffle is provided to insure the impingement of the sweeping gases upon the charge at all times during their passage through the furnace. In Fig. 4 means for employing subsurface heating of the charge are shown which is of advantage when working with some kinds of materials. Other modifications may be made in the construction of the furnace within the scope of the invention. For example, a false arch may be substituted for the fire tubes as the combustion chamber and it is even possible to substitute electrical heating units and supply the sweeping gases from an outside source.

The efficiency of the improved furnace of the invention is well illustrated by the following comparative results obtained in the volatilization of antimony trioxide. In one instance a prior art furnace was used in which combustion gases were passed over the charge in the ordinary manner and the rate of volatilization was found to be one pound per hour for each square foot of hearth area. In two other instances a furnace was used which was heated by means of tubes of silicon carbide suspended in the upper part of the furnace laboratory and the hot gases of combustion reversed and passed back through the laboratory above the charge of impure antimony oxide. In both of these cases the temperature was 900° C. but in the first furnace which was not equipped with baffles the rate of volatilization was three pounds per hour for each square foot of hearth area and the product was only of fair quality. In the second furnace, equipped with inlet and outlet baffles as shown in the drawings, the rate of volatilization was sixteen pounds per hour for each square foot of hearth area and the product was of excellent quality.

It is believed that the improved results attending the use of furnaces constructed in accordance with the invention are to be attributed in the main to the heating of the charge by radiation while simultaneously sweeping the charge with the gases in the manner shown. In volatilizing substances in such furnaces, abundant heat is radiated directly to the very molecules passing from the condensed to the vapor state thus rendering the operation virtually independent of the high heat resistivity of surface films to convected heat which factor is the prime enigma of many of the prior art furnaces. At the same time, the

unique manner in which the combustion gases are jetted or impinged against the charge enables more heat to be extracted therefrom than when the gases are merely passed through the laboratory of the furnace.

It is well known that heat is absorbed when substances, for example, arsenious oxide or antimony oxide, are volatilized and the transmission of heat from hot gases to a substance undergoing volatilization is more difficult than if the substance were substantially non-volatile. As the amount of heat of volatilization is of considerable magnitude, it is evident that unless sufficient heat can be constantly imparted to the substance, the rate of volatilization must necessarily be low. Inasmuch as furnaces in which the hot gases are simply passed through the furnace do unquestionably give low rates of volatilization as compared to the improved furnace of the invention, it is believed that the primary reason for such low rates is due to inadequate transmission of heat due mainly to the difficulty of causing convected heat to travel downwardly in a furnace and to the fact that the vapors evolved from the charge flow against the hot gases thus preventing the latter from intimately contacting the surface of the charge. By the present invention heat is radiated to the charge and the sweeping gases directly contact same by reason of the novel construction of the furnace.

It will thus be appreciated that the present invention provides many advantages in the treatment of a great variety of chemical and metallurgical substances. While certain novel features of the invention have been disclosed and are pointed out in the annexed claims, it will be understood that various omissions, substitutions and changes may be made by those skilled in the art without departing from the spirit of the invention.

What is claimed is:

1. In a furnace, a main chamber, fire tubes positioned in the upper portion of said chamber, said fire tubes interconnecting burners and a second chamber, an inlet port connecting said main and second chamber, an outlet port connecting said main chamber with a suitable flue system and baffles so positioned with respect to said inlet and outlet ports, that gases passed through said port impinge upon the hearth of said main chamber.

2. In a furnace, a main chamber, fire tubes positioned in the upper portion of said chamber interconnecting burners and a second chamber, an inlet port connecting said main and second chamber, an outlet port connecting said main chamber with a suitable flue system, baffles associated with said inlet and outlet ports for deflecting gases onto the hearth of said chamber and an auxiliary gas inlet in said second chamber.

3. A furnace comprising a main furnace chamber having a hearth, charging means associated therewith, heating means in the upper portion of said chamber for burning fuel out of contact with the furnace charge, inlet and outlet ports in the walls of said main chamber, baffles associated with said ports and a second chamber adapted to receive combustion gases from said heating means and supply them to the inlet port.

4. In a furnace, a chamber having a solid hearth, inlet and outlet ports in the walls of said chamber, baffles associated with said ports, heating means for radiating heat to a charge on said hearth from fuel burned out of contact with said charge and means for circulating combus-

tion gases from said heating means to said chamber and over a charge on the hearth via said ports.

5. A furnace comprising a main chamber having a hearth adapted to support a charge, fire tubes positioned in said chamber above said hearth, a second chamber connected to the exits of said fire tubes, a port connecting said main and second chambers and a baffle disposed in the travel of gases from said port for directing them downwardly onto said charge.

6. A furnace comprising a main furnace chamber, fire tubes positioned in the upper portion of said chamber, a second chamber adapted to receive combustion gases from said fire tubes, means for supporting a charge in the lower portion of said chamber, an auxiliary heating apparatus for supplying heat to the charge, an inlet port for supplying combustion gases from said 20 second chamber to the charge, an exit port connecting said main chamber to a flue and baffles associated with said inlet and outlet ports to deflect the combustion gases and cause same to sweep the charge.

25 7. In a furnace, a hearth, means for burning fuel out of contact with a charge supported on said hearth to supply heat to the charge by radiation, means for receiving the combustion gases and recirculating them through the laboratory of the furnace and baffles positioned to jet the gases against the charge and sweep same during the entire passage of the gases through the laboratory of the furnace.

8. A furnace comprising a main chamber, a 35 mixing chamber, fire tubes in said main chamber and communicating with said mixing chamber, an auxiliary gas inlet associated with said mixing chamber, an inlet port connecting said chambers, an outlet port leading from said main chamber 40 to a flue system and baffles in said main chamber so positioned that gases passed through the main chamber via said ports are jetted against the charge in said main chamber.

45 9. A furnace comprising a main chamber, a mixing chamber, means for burning fuel out of contact with the charge in the main chamber the gas exit from said means terminating in said mixing chamber, an auxiliary heating element for sub-surface heating of the charge in the main chamber, an inlet port connecting said chambers,

an outlet port leading from the main chamber to a suitable flue and means in said main chamber for deflecting and impinging gases passed through said main chamber via said ports against the charge in said main chamber.

5

10. A furnace of the muffled-flame type comprising the combination with a chamber defining a hearth for receiving a charge to be heated, of burners for the furnace, refractory conduit associated with the burners extending through the 10 hearth chamber of the furnace and in the interior of which conduits combustion proceeds, an auxiliary chamber communicating with the conduits for receiving combustion gases therefrom, means for the auxiliary chamber enabling the 15 composition and temperature of the combustion gases to be predeterminedly controlled and means for leading the said combustion gases from the auxiliary chamber into the hearth chamber.

10

11. A furnace of the muffled-flame type comprising the combination with a chamber having a hearth for receiving a charge of material to be heated, of an auxiliary chamber for receiving combustion gases, gas ports interconnecting the auxiliary chamber with the hearth chamber, 25 heating means for radiating heat to a charge on the hearth from fuel burned out of contact with the charge, means for circulating combustion gases from the heating means into the auxiliary chamber and thence into the hearth chamber 30 through the said ports, and baffles for directing the products of combustion into intimate contact with the charge on the hearth.

20

12. In the furnace treatment of volatile compounds, the improvement which comprises heating the charge predominantly with radiant heat by fuel burned out of contact with the charge and recirculating the combustion gases back over the charge in such manner that they impinge thereon thereby rapidly volatilizing the charge.

35

13. The process for treating volatile substances which comprises charging the material to the hearth of a furnace and heating the material predominantly by radiation while simultaneously and continuously impinging hot gases against 45 substantially the entire surface of the charge whereby the material is volatilized at an extremely high rate.
